UNITED STATES PATENT OFFICE.

HERMAN P. FEST, OF SAN DIEGO, CALIFORNIA.

HOLDER FOR PHOTOGRAPHS, CARDS, PLATES, OR SIMILAR ARTICLES.

Application filed April 19, 1924. Serial No. 707,669.

My invention relates to holders for holding photographs, price cards, name plates or similar articles, and the objects of my invention are: first, to provide a holder of this class whereby photographs, price cards, name plates or other similar articles are supported by the same in such a manner that no part of the outer borders thereof can be seen from the front of the holder, and whereby 10 said photographs, cards, plates or other similar articles are held in position against the back side of the portion of the holder surrounding the opening therein by means of a resilient member at the back side of said 15 holder; second, to provide a holder of this class in which the resilient retaining member for removably retaining said photograph, card, plates or other similar article in position extends substantially across the 20 opening in the holder and upwardly from the lower side thereof; third, to provide a holder of this class in which said resilient retaining member forms a pocket at its lower portion, between the same and the main front 25 portion of the holder contiguous to the lower side of the opening therein, for supporting the lower edge of the article positioned at the back side of said holder; fourth, to provide such a holder in which the resilient retaining 30 member is formed an integral part of the main front portion of the holder; fifth, to provide a holder of this class in the form of a frame which is provided with backwardly extending legs which are formed an integral 35 part of the holder; sixth, to provide as a whole a novelly constructed device of this class, and seventh, to provide such a device which is particularly simple and economical of construction, durable, and which will not 40 readily deteriorate or get out of order.

With these and other objects in view, as will appear hereinafter, my invention consists of certain novel features of construction, combination and arrangement of parts and 45 portions, as will be hereinafter described in detail and particularly set forth in the appended claims, reference being had to the accompanying drawings and to the characters of reference thereon, which form a part 50 of this application, in which:

Figure 1 is a perspective view of my holder in the form of a picture frame; Fig. 2 is a sectional elevational view thereof, taken through 2—2 of Fig. 1; Fig. 3 is a front elevational view of a price card tag holder incorporating my invention; Fig. 4 is a longi-

tudinal sectional view thereof, taken through 4—4 of Fig. 3; Fig. 5 is a perspective view of my holder adapted for holding price cards or name plates; and Fig. 6 is a sectional elevational view thereof, taken through 6—6 of Fig. 5.

Like characters of reference refer to similar parts and portions throughout the several views of the drawings.

My invention, when embodied in a picture frame, as shown in Figs. 1 and 2 of the drawings, consists of a front plate or frame member 1, legs 2 for supporting the same and a resilient picture or photograph retaining member 3. The frame member 1 is provided with an opening 1^a near the upper end thereof, said opening being of any shape desired and the portion of the frame surrounding said opening being bent or formed inwardly, as indicated by 1^b in Fig. 2 of the drawings. To each side of the frame member 1 are secured backwardly extending legs 2, which are formed integrally with the front plate or frame member 1, the front edges of said legs being inclined at an angle with the vertical to provide an angular position for the frame member 1 and also greater stability for the holder. The resilient retaining member 3, for supporting the picture or photograph in position against the back side of the frame member 1 over the opening therein, is formed integrally with the frame member 1 from the portion of said frame member stamped out or bent backwardly from the portion of the frame member forming said opening 1^a. Said resilient retaining member 3 is bent backwardly forming the lower side of the opening 1^a, as indicated by 3^a in Fig. 2, and is then bent downwardly below the portion 3^a and upwardly, forming a pocket 3^b for receiving and supporting the lower edge of the picture or photograph positioned therein, at the same time concealing said lower edge from the front side of the picture frame. It will be here noted that the backwardly or inwardly bent portions 1^b of the frame member 1 and the downwardly bent portion of the member 3 are preferably made substantially in the same plane so that a picture positioned in the pocket of the member 3 will bear evenly at all sides near its edges against the back side of the holder. The retaining member 3, being resilient, and bent inwardly at its upper end, bears against the picture positioned in the pocket thereof and resiliently holds the same in position.

It will be noted that if it is desired to use the picture frame as a novelty or souvenir, there is provided a space between the lower side of the opening and the lower edge of the frame member 1 for imprinting or impressing the name of the city or locality adapted to be designated.

In Figures 3 and 4 of the drawings I have shown the embodiment of the above mentioned resilient retaining means of my invention in a hanging price card holder, the opening in the frame member 1 being also positioned to one side or to the upper end to provide a space for the manufacturer's name 15 of the goods to which the price card holder is applied.

The price card or name plate holder shown in Figs. 5 and 6 of the drawings is constructed similarly to the picture frame shown in Figs. 1 and 2 except that the frame member 1 and the opening therein are of considerably greater length and extend in a horizontal position, the same being, however, positioned at an angle with the vertical by legs as described in connection with the picture frame in Figs. 1 and 2.

It is obvious from this construction, as illustrated in the drawings and disclosed in the foregoing specification, that there is provided a holder for holding photographs, price cards, name plates or other similar articles as aimed at and set forth in the objects of the invention, and though I have shown and described a particular construction, combination and arrangement of parts and portions and certain modifications and embodiments thereof, I do not wish to be limited to this particular construction, combination and arrangement nor to the modifications or embodiments disclosed, but desire to include in the scope of my invention, the construction, combination and arrangement sub-

stantially as set forth in the appended claims.

Having thus described my invention, what I claim as new and desire to secure by Letters Patent, is:

1. In a holder of the class described, a frame member provided with an opening therein, the portion of said frame member stamped out to form said opening being bent 50 backwardly and downwardly and thence upwardly in spaced relation from said frame member below the lower edge of said opening and extending over a portion of said opening, the space between said downwardly bent portion and the one end of said upwardly bent portion forming a pocket below the lower edge of the opening of the frame member.

2. In a holder of the class described, a frame member provided with an opening therein, the portion of said frame member surrounding said opening being bent inwardly at its inner edge forming a continuous bearing portion around said opening at the back side thereof for the edge portion of a picture or the like, and the portion thereof stamped out to form said opening being bent inwardly and downwardly below the lower edge of the opening and thence upwardly in spaced relation from said frame member below the lower edge of said opening and extending over a portion of said opening forming a pocket between said downwardly bent portion and the lower end of said upwardly bent portion and below the lower edge of the opening of said frame member, the inwardly bent portion surrounding said opening being substantially in the same plane with said downwardly bent portion.

In testimony whereof, I have hereunto set 80 my hand at San Diego, California, this 12th day of April, 1924.

HERMAN P. FEST.
